UNITED STATES PATENT OFFICE.

ALBERT F. SAUNDERS, OF SYRACUSE, NEW YORK, ASSIGNOR TO T. N. BENEDICT
MFG. CO., OF EAST SYRACUSE, NEW YORK.

DESIGN FOR A CAKE STAND.

Application filed January 31, 1928. Serial No. 25,088. Term of patent 3½ years.

To all whom it may concern:

Be it known that I, ALBERT F. SAUNDERS, a citizen of the United States, residing at 106 Rugby Road, city of Syracuse, county of Onondaga, and State of New York, have invented a new, original, and ornamental Design for a Cake Stand, of which the following is a specification, reference being had to the accompanying drawing, forming a part thereof, wherein—

Fig. 1 is a side elevation of the cake stand showing my new design.

Fig. 2 is a top plan view of the cake stand.

Fig. 3 is a diagrammatic plan view of the cake stand shown in Fig. 1.

I claim:

The ornamental design for a cake stand substantially as shown.

In testimony whereof, I have hereunto signed my name at East Syracuse, in the county of Onondaga and State of New York this 27th day of January, 1928.

ALBERT F. SAUNDERS.
